UNITED STATES PATENT OFFICE

2,440,860

SWIRL-HEAD SEPARATOR

Walter J. Kalmeyer, Glenshaw, Pa., assignor to
 Blaw-Knox Company, Pittsburgh, Pa., a corporation of New Jersey

Application September 14, 1946, Serial No. 697,050

2 Claims. (Cl. 183—102)

1

My invention relates to apparatus for removing suspended particles of liquid from gases and particularly to an improved construction of swirl-head separator. Such apparatus is commonly used for cleaning natural gas, as well as for treatment of divers other gases, and one form thereof is illustrated in Sillers Patent 1,917,606. As shown therein (see particularly Figures 4—6), the apparatus in general comprises a series of spiral plates arranged in spaced relation about a vertical axis and enclosed within a cylindrical casing. The inner edges of the curved plates define a vertical cylindrical void which serves as an inlet passage. The outer edges of the plates lie in the surface of a cylinder and the space between them and the casing affords an annular outlet passage.

The curved plates are framed at their upper and lower edges into circular horizontal plates or discs, the lower of which forms a pan for collecting the separated liquid and has a central opening communicating with the inlet void. The upper plate overlies the spiral plates and the central void thereby forcing gases entering the latter to escape by flowing in spiral paths between the plates to the annular outlet passage. Each of the curved plates is provided at spaced intervals with vertical channel-shaped ribs, extending between the horizontal plates. These ribs serve the combined function of providing separating obstructions in the spiral passage between the curved plates and drainage channels for the separated liquid.

The construction of separators as described above has heretofore been attended by considerable difficulty. The curved plates (particularly if of large size) are difficult to form accurately and to assemble in properly spaced relation to provide spiral gas passages of uniform width therebetween; and this difficulty is increased by the necessity of providing the aforementioned separating ribs or channels at intervals on the plates.

An object of my invention is to provide a swirl head for separators which is relatively inexpensive to fabricate and yet may be accurately assembled to provide narrow gas passages of precise width without difficulty. Another object is to produce swirl-head separators of improved performance by providing a construction which may be easily made to conform accurately to the design dimensions in all parts, and free from the dimensional deviations from theoretical design usually encountered and necessarily tolerated in separators of previously known construction.

In a preferred embodiment of the invention, I form the spiral passages by assembling in proper relation a plurality of plane pieces of plate. Each spiral passage wall comprises several such plates

60 disposed side by side with their vertical edges overlapping, and having bends adjacent said edges whereby they form a generally spiral-shaped wall made up of a series of flat surfaces instead of being a continuous curve. The edges of each plate beyond the laps or joints is shaped to extend outwardly from the next plate and thus provide liquid separating and collecting channels or ribs on opposite sides of the element adjacent each joint. The laps or joints of the several spiral walls are disposed in radial alignment, and have holes therethrough so that they may be assembled upon radial rods or spokes, with pipe spaces between adjacent plates.

10 A clear understanding of the construction outlined above may be obtained from the following detailed description which refers to the accompanying drawings illustrating the present preferred embodiment. In the drawings,

15 Figure 1 is a vertical axial section through a separator having the swirl head of my invention mounted therein;

20 Figure 2 is a partial horizontal section taken along the plane of line II—II of Figure 1;

25 Figure 3 is a horizontal section taken along the plane of line III—III of Figure 1; and

30 Figure 4 is a partial horizontal section taken along the plane of line IV—IV of Figure 1.

Referring in detail to the drawings, my improved swirl head is shown mounted in a casing 1 which is preferably a pressure vessel of substantial wall thickness, having a gas inlet 2 in the side and a gas outlet 3 in the top. The swirl head, indicated generally at 4, is disposed in the upper end of the casing, being supported upon and conveniently secured to a circumferential ring or flange 5 welded in the casing. The swirl head 4 includes a bottom plate 6 having a central opening with an inlet guide ring 7 seated therein and drain tubes 8 depending from diametrically opposite points. A cap plate 9 on top of the head has radial spacer bars 10 secured thereto. A plurality of banks of spaced substantially parallel plates 11 through 19 are disposed about and spaced from the axis of the head to define a plurality of continuous gas passages of generally spiral shape. In the example illustrated, the head is composed of eight banks of plates, the adjacent edges of successive banks overlapping and secured together by radial tie bolts 20 and spacer sleeves 21, and vertical tie bolts 22 extending through cap plate 9 and bottom plate 6.

45 The vessel 1 is adapted to hold a pool of liquid in the bottom formed by the accumulation of separated particles of liquid draining through pipes 3 from the bottom of the swirl head. Any convenient means may be provided for removing the liquid or controlling its level. The liquid level should, however, be high enough to provide a

head above the lower ends of pipes 8 exceeding the pressure drop through the swirl head with normal or preferably maximum rate of gas flow therethrough. The pool then acts as a liquid seal.

The gas entering the inlet 2 is apt to form a vortex in the vessel below the swirl head as an up-stream result of the vortex produced within the swirl-head core. To avoid this, I provide the collar 7 with a plurality of transverse baffles or swirl-stoppers 7a. By this means, the overall pressure drop through the apparatus may be appreciably reduced. Other gas-treating apparatus may, of course, be mounted between the pool and the swirl head, such as various gas-and-liquid contact devices. The presence of such devices makes it even more desirable to prevent a vortex from forming below the swirl head inlet.

A deflector 23 is mounted adjacent the inner end of the inlet 2 to divide inflowing gases between paths in opposite directions around the vessel and effect a gradual transition to generally upward flow toward the central void in the swirl head. The ascending liquid-laden gas enters the swirl head at the bottom, passing upwardly through collar 7 between baffles 7a, and thence flows outwardly through the continuous spiral passages defined by the banks of plates 11 through 19. The construction of the assembly of plates is shown more clearly in Figure 2. As there shown, the innermost of the plates, 11 and 12, approach the void in the head generally tangentially, and divide it into a plurality of passages spiralling outwardly. The walls of these passages comprise two adjacent series of overlapping plates. One is the series of plates 11, 13, 15, 17 and 19, of successive banks and the other is the series 12, 14, 16, and 18. Since eight banks of plates are used, there are eight concentric spiral passages. The edges of the plates extend beyond the overlapping portions thereof. Plates 11 and 19 are shorter than the others, plates 11 being unsupported at their inner ends, while plates 19 are supported at their outer ends by tie rods 22, approximately midway between the outer ends of the bolts 23. I prefer to weld plates 19 to the rods 22 after assembly. The overlapping edges of successive plates of the series are held tightly together by pressure of the spacers 21 on opposite sides of the lap, resulting from the tension in the tie rods 20 passing through the plates (which are punched for this purpose) and the pipe spacers 21. Considering each series as beginning at the central void and ending at the outer circumference of the head, the laps are formed with the rearmost plate radially inside the next forward plate and so on. Each plate after the first is bent on the forward side of the lap at the correct angle to extend to the next lap in the spiral series. It is also bent at its rear edge at a small distance from the next forward plate to form a series of vertical channels or troughs 24 in the spiral gas passages on the inner side of the passage. Each rear plate is bent back on itself at its forward edge, as shown at 25, providing a series of troughs or channels on the outer side of the several gas passages. The extreme outer ends of plates 19 are similarly bent as shown. The channels 24 and 25 extend approximately midway into the spiral gas passages from opposite sides and effectively remove drops of liquid from the gas passing through the passages. The liquid flows down the troughs and collects on the bottom plate 6, overflowing eventually through drain pipes 8.

It will be apparent from the foregoing that the construction disclosed herein has numerous ad-

vantages over that known heretofore. In the first place, the spiral passages for the outflowing gas are formed exclusively from generally flat plates having their edges bent at an angle thereto. The formation of the plates is a simple matter and may easily be effected by suitable dies. The individual plates of each bank are duplicated in the several banks and the assembly of the plates into banks and the banks into a complete head is a simple matter. The radial tie bolts and spacer sleeves insure the proper positioning of the plates relative to each other to provide passages of uniform width throughout. The bending of the extreme edges of the plates to form drop-trapping channels further simplifies the construction and reduces the cost thereof.

Although I have illustrated and described but a preferred embodiment of the invention, it will be recognized that changes in the details of the construction disclosed may be made without departing from the spirit of the invention or the scope of the appended claims.

I claim:

1. A swirl head for a separator comprising a plurality of banks of plates, the plates of each bank being generally flat and substantially parallel, the banks being disposed side by side about and spaced from a common vertical axis with the edge of each plate of any one bank overlapping the edge of a plate in the adjacent bank which is more remote from said axis, whereby the plates of the several banks define a plurality of continuous, generally spiral passages for outward flow of liquid-bearing gas from the region adjacent said axis, each passage including a plurality of rectilinear portions, the extreme rear edge of the outer plate of each pair of overlapping plates of adjacent banks being spaced from the inner one to form a drop-trapping channel.
2. A swirl head for a separator comprising a plurality of banks of plates, the plates of each bank being generally flat and substantially parallel, the banks being disposed side by side about and spaced from a common vertical axis with the edge of each plate of any one bank overlapping the edge of a plate in the adjacent bank which is more remote from said axis, whereby the plates of the several banks define a plurality of continuous, generally spiral passages for outward flow of liquid-bearing gas from the region adjacent said axis, each passage including a plurality of rectilinear portions, the extreme forward edge of the inner plate of each pair of overlapping plates of adjacent banks being bent back on itself to form a drop-trapping channel.

WALTER J. KALMEYER.
